HANDLE FOR PORTABLE PICTURE SCREENS OR THE LIKE

Frank J. Prokop, Chicago, Ill., assignor to Da-Lite
Screen Company, Inc., Chicago, Ill., a corpora-
tion of Illinois

Application February 27, 1953, Serial No. 23,816

Term of patent 3½ years

(Cl. D61—1)

To all whom it may concern:

Be it known that I, Frank J. Prokop, a citizen
of the United States of America, residing at
Chicago, in the county of Cook and State of Illi-
nois, have invented a new, original, and orna-
mental Design for a Handle for Portable Picture
Screens, or the like, of which the following is a
specification, reference being had to the accom-
panying drawing, forming part thereof:

Figure 1 is a side view of a handle for portable
picture screens or the like, showing my new
design.

Fig. 2 is a front elevational view.

Fig. 3 is a top plan view, and
Fig. 4 is a bottom plan view thereof.

I claim:

The ornamental design for a handle for port-
able picture screens or the like, as shown.

FRANK J. PROKOP.
